RESILIENT WHEEL

Webster Warn Little, National Park, N. J., assignor of twenty-five per cent to Senga Morrison Ives, New York, N. Y.

Application January 27, 1941, Serial No. 376,209

3 Claims. (Cl. 152—105)

The present invention relates to new and useful improvements in resilient wheels and has for its primary object to provide, in a manner as hereinafter set forth, a device of this character which is adapted to absorb road shock in addition to materially reducing the unsprung weight of the vehicle.

Another very important object of the invention is to provide a wheel of the aforementioned character comprising what may be referred to as a floating rim mounting, the construction and arrangement being such as to permit limited circumferential as well as radial movement of the rim and tire relative to the wheel.

Other objects of the invention are to provide a resilient wheel of the character described which will be comparatively simple in construction, strong, durable, highly efficient and reliable in use, compact, light in weight, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a resilient wheel constructed in accordance with the present invention, portions being broken away to expose the inner elements.

Figure 2 is a cross sectional view through a portion of the wheel, taken substantially on the line 2—2 of Figure 1.

Figure 3 is a plan view of a portion of the floating channel ring.

Figure 4 is a fragmentary view in section, taken substantially on the line 4—4 of Figure 1.

Figure 5 is a cross sectional view, taken substantially on the line 5—5 of Figure 1.

Figure 6 is an elevational view of a portion of one of the side rings, looking at the inner face thereof.

Referring now to the drawings in detail, it will be seen that the embodiment of the invention which has been illustrated comprises a pair of complementary disks 1 of suitable metal. The disks 1 have formed therein centrally located openings 2 which accommodate the portion 3 of a conventional hub 4. The disks 1 further include inwardly offset abutting flanges 5 which are removably secured to the hub 4 through the medium of studs 6 and nuts 7, said flanges being apertured for the reception of the studs.

Mounted between the inner portions of the disks 1 is an annulus 8 of suitable metal, said annulus being substantially U-shaped in cross section. The annulus 8 is secured between the disks 1 by bolts 9. The annulus 8 has pressed outwardly therein, at circumferentially spaced points, substantially concave apertured seats 10 the purpose of which will be presently set forth.

Slidably mounted between the outer portions 10 of the disks 1 is a channel ring 11. The side walls 12 of the channel ring 11 are provided with laterally offset outer portions 13. Mounted on the outwardly offset portions 13 of the channel ring 11 and extending inwardly therefrom for sliding contact with the outer faces of the disks 1 is a pair of flat side rings 14. Mounted in the inner faces of the side rings 14 are packings 15 which prevent the passage of foreign matter, such as mud and water, between said side rings and the disks 1.

The channel ring 11 has formed therein, at spaced points, circumferentially elongated openings or slots 16 for alignment with the openings 17 in the seats 10. Passing through the openings 16 and 17 are bolts 18 which yieldingly connect the channel ring 11 to the annulus 8. Threaded for adjustment on the inner end portions of the bolts 18 are rounded nuts 19 which are rockably engaged in the concave seats 10. Coil springs 20 encircle the bolts 18 between the channel ring 11 and the annulus 8. Washers 21 are mounted on the headed outer end portions of the bolts 18. Mounted on the outer portions of the bolts 18, between the washers 21 and the channel ring 11, are coil springs 22.

Bolts 23 secure the side rings 14 to the offset portions 13 of the channel ring 11. The peripheral portions of the elements 13 and 14 are adapted to receive and support a demountable rim 24 which carries a pneumatic tire 25. Lugs 26 are provided on certain of the bolts 23 for retaining the demountable rim 24.

It is thought that the manner in which the invention functions will be readily apparent from a consideration of the foregoing. As the wheel travels over irregularities the channel ring 11 moves inwardly and outwardly, also circumferentially, between the disks 1, said channel ring being floatingly supported between the coil springs 20 and 22. The slots 16 through which the bolts 18 pass allow limited circumferential movement of the channel ring 11 relative to the annulus 8, the rounded nuts 19 rocking in the seats 10 when such movement occurs. The openings 17 are sufficiently large to permit movement of the bolts 18

in this manner. The tension of the coil springs 20 and 22 may be regulated as desired through the medium of the nuts 19.

It is believed that the many advantages of a resilient wheel constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:

1. A resilient wheel comprising a pair of spaced disks, a fixed annulus mounted between said disks and forming a brace for the disks, a channel ring having its base portion slidably mounted between the disks, bolts loosely connecting the channel ring to the annulus, coil springs mounted on the bolts between the channel ring and the annulus, coil springs mounted on the bolts between the outer ends thereof and the channel ring, and means for securing a rim on the outer edge of said channel ring.

2. A resilient wheel comprising a pair of spaced disks, means for securing said disks to a hub, an annulus fixed between the disks and forming a brace for the disks, a channel ring having its base

portion slidably mounted between said disks, resilient means yieldingly connecting the channel ring to the annulus for radial and circumferential movement relative to the disks, the channel ring including outwardly projecting side walls comprising offset peripheral portions, side rings mounted on said outwardly offset peripheral portions and slidably engaged with the outer faces of the disks, and means for securing a rim on the channel ring and the side rings.

3. A resilient wheel comprising a pair of spaced disks, a fixed annulus mounted between said disks, substantially concave seats projecting outwardly from the annulus and having openings therein, a channel ring slidably mounted between the disks outwardly of the annulus, said channel ring having circumferentially extending slots therein, bolts passing through the openings and the slots, washers mounted on the outer end portions of the bolts, coil springs mounted on the bolts between said washers and the channel ring, coil springs mounted on the bolts between said channel ring and the annulus, rounded retaining nuts threaded on the inner end portions of the bolts and rockably engaged in the seats, and means for securing a rim on the channel ring.

WEBSTER, WARN, LITTLE.
